UNITED STATES PATENT OFFICE

THOMAS A. BANNING, JR., OF WILMETTE, ILLINOIS

AUTO LIFT AND THE LIKE

Application filed May 13, 1930. Serial No. 452,041.

This invention relates to certain improvements in lifts for raising automobiles and the like. The lift herein disclosed is especially intended for the raising of automobiles in 5 and around service stations, garages, greasing and oiling plants, and similar locations. It will be understood, however, that the features of the invention are not limited to the foregoing or any other specific classes of service. In as much, however, as the lift herein disclosed is especially intended for the foregoing classes of service, I have illustrated and 10 will describe its usefulness in that connection; but in so doing I wish it distinctly understood that I do not intend to limit myself 15 except as I may do so in the claims.

One object of the invention is to provide a lift having a minimum number of moving parts in frictional contact with each other 20 and under fluid pressure so as to require sealing against seepage of the fluid. In this connection it is an object to provide a lift which may be operated by any suitable fluid pressure, either air or oil or other suitable fluid. 25 The lift is so arranged, however, that the moving parts which are subject to frictional contact with each other are at all times efficiently lubricated and sealed by an oil seal so as to reduce or completely avoid fluid 30 seepage.

A further feature of the invention relates to the provision of a lift having a stationary upstanding piston member, the lower end of which is effectively anchored in a very rigid 35 manner; together with a surrounding and overlying vertically movable cylinder member which travels upwardly with respect to the stationary piston member, said cylinder member carrying at its upper end the platform or structure which supports the automobile. In connection with the foregoing it is an object to provide a structure of such arrangement that the lower portion of the stationary piston member may be very rigidly 40 anchored so as to establish a very rigid upstanding column fully capable of resisting the lateral forces or any bending tendency which may be created in service due to eccentric loading.

50 It is a further object in connection with the

foregoing to construct the piston member in the form of a stationary hollow column or tubular member of maximum size consistent with the desired cylinder size. This will also materially increase the stiffness and 55 rigidity of the piston column.

A further feature of the invention relates to the provision of an arrangement for establishing an abutment plate surrounding the vertically movable cylinder substantially at 60 the ground level and very rigidly supported. This abutment plate serves to receive and resist any lateral deflection of the cylinder. This stationary abutment plate is preferably 65 located close to the ground level and preferably does not actually make sliding contact with the exterior of the cylinder during normal vertical movements thereof, thereby avoiding any frictional contact between parts during the normal lifting and lowering operations. This makes it unnecessary to finish the exterior surface of the vertically movable cylinder and also makes it unnecessary to provide special antifriction devices such as 70 rollers; while at the same time there is ample provision for receiving and resisting lateral deflection of the column when raised and under load.

A further feature of the invention relates to the provision of a ground shell which surrounds and protects the vertically movable cylinder and extends down at least as far as the lower limit of movement of the lower end of the cylinder. This ground shell thus effectively prevents the ingress of dirt and other foreign or gritty substance. Furthermore, the ground shell may, if desired, be wholly or partially filled with liquid oil so as to lubricate the exterior surface of the 85 shell where the same passes through the abutment or ground plate, to thereby insure effective lubrication of the same in those instances when actual contact is established between these parts.

A further feature of the invention relates to the provision of a construction in which the lower end of the ground shell is rigidly connected to the lower portion of the piston member. This serves to seal the lower portion 95 of the ground shell chamber at the same 100

time it serves to rigidly connect the stationary piston and the ground shell so that the rigidity of the ground shell imbedded in the earth or concrete is available to improve or 5 reenforce the rigidity of the stationary piston member. This will insure an extremely rigid combined structure.

A further feature in connection with the foregoing is the provision of an arrangement 10 in which the lower portion of the stationary piston member reaches a considerable distance below the lower end of the ground shell at the point where these two elements are rigidly connected together. This arrangement 15 is beneficial since it makes it possible to imbed the lower portion of the piston member directly in the concrete or earth so that the stationary piston member is supported with an increased amount of stiffness and 20 rigidity and supplemental to the reinforcing action of the ground shell itself.

A further benefit secured from the foregoing arrangement is that in those cases in which it is desired to increase the tank capacity 25 of the stationary tubular piston member, such increase of capacity may be procured by extending the stationary tubular piston member further down into the ground until the desired capacity is established, and 30 without the necessity of correspondingly lengthening the movable cylinder member or the ground shell. It is thus possible to secure such increased capacity at a minimum of cost and weight of structure.

35 A further feature of the invention relates to the provision of an arrangement in which there is provided if necessary a sealing device on the upper end of the stationary piston member and inside of the vertically movable 40 tubular cylinder member. Such a sealing device may be either in the form of a packing gland or a cup leather or other suitable device. In this connection it is an object of the invention to provide an opening in the 45 platform or top member at the upper end of the vertically movable cylinder so as to give access to this packing device for replacement or repair or adjustment by the simple expedient of removing a cover provided for 50 that purpose when the lift is in the lowered position.

A further feature of the invention is to provide an arrangement such that the bearing surface at the upper end of the stationary 55 piston member may be made ample to give suitable and sufficient support in contact with the inner surface of the vertically movable cylinder to transmit the deflecting forces created by eccentricity of load when 60 the lift is raised.

Another feature of the invention relates to the provision of a lift arrangement of self-contained nature including tankage capacity within itself sufficient to accommodate the 65 full amount of oil necessary to operate the

lift as an oil lift when it is desired to use this system of operation. In this connection it is an object to establish within the stationary tubular piston member a sufficient amount of oil storage capacity to accommodate the oil necessary for a complete lifting operation 70 so that it is unnecessary to make special provision for supplemental and external ground or other tanks for oil storage.

In connection with the foregoing, I have 75 discovered the fact that when using a stationary tubular piston member of substantially full size corresponding to a specified diameter of movable cylinder, and when the lower portion of said stationary tubular piston is carried down and imbedded in the ground below the lower end of the ground shell, an amount sufficient to give a rigid piston support, the space within said hollow piston is sufficient to accommodate all of the oil necessary for a complete lifting operation without the necessity of external storage capacity. This further shows a peculiar and definite relationship existing between the arrangement 85 of parts disclosed in the present application. 90

A further feature in connection with the foregoing is the provision of piping arrangements such that when the device is used as an oil lift by operation of compressed air or the like, said compressed air is admitted through an air pipe into the upper portion of the hollow piston member, there being an oil pipe reaching from the lower portion of the hollow piston member up through the piston head into the movable cylinder above the same so that it effects the lifting operation. During the lowering operation it is only necessary to release said air under control whereupon the oil is again restored from the movable cylinder member down to the hollow piston member. 100

A further feature of the invention relates to the provision of a stop on the vertically movable cylinder member in position to engage the ground ring and arrest the upward movement of the cylinder prior to disengagement thereof from the upper portion of the stationary piston member. 110

A further object of the invention is to provide a structure which can be readily manufactured as a complete assembly in the shop, ready for permanent placement in the ground at the location of the purchaser or user, without other necessary operations than the excavation of a suitable ground opening, the connection of a single pipe, and suitable tamping or concrete placing operations around the structure. 115

A further feature in connection with the foregoing is the provision of a structure 120 which may be readily built and assembled by welding or brazing or other similar operations in the shop.

A further feature of the invention relates to the provision of a new and improved con- 125

struction of platform arrangement for supporting the car. In this connection it is an object to provide a platform structure of very simple design and construction, and one which can be readily made from structural forms and simple operations.

Other objects and uses of the invention will appear from a detailed description of the same which consists in the features of construction and combinations of parts herein-after described and claimed.

In the drawings:

Figure 1 shows a vertical central section through a lift embodying the features of the present invention, together with the platform at the upper end of the vertically movable cylinder, the platform being shown in transverse section, and the parts being shown in lowered position;

Figure 2 shows a view similar to that of Figure 1 but on somewhat reduced scale the parts being shown in raised position;

Figure 3 shows a plan view of the structure on reduced scale as compared to Figure 1;

Figure 4 shows a horizontal section on the line 4—4 of Figure 1, looking in the direction of the arrows;

Figure 5 shows a horizontal section on the line 5—5 of Figure 1, looking in the direction of the arrows;

Figure 6 shows a horizontal section on the line 6—6 of Figure 1, looking in the direction of the arrows;

Figure 7 shows a horizontal section on the line 7—7 of Figure 1, looking in the direction of the arrows;

Figure 8 shows a horizontal section on the line 8—8 of Figure 1, looking in the direction of the arrows; and

Figure 9 shows a fragmentary detail vertical section through the upper portion of the cylinder and piston structure and related parts in lowered position, but illustrating a modified type of construction in which a cup-leather is provided for establishing the seal instead of an adjustable packing gland.

Referring to the drawings, there is a stationary tubular piston 11, the lower end 12 of which is closed; this lower portion 12 may be integral with the tubular portion 11 or may constitute a cap or other cover closely welded or otherwise secured in place in a fluid tight fashion.

A cap 13 is secured on the upper end of the tubular member 11. For this purpose said cap 13 is preferably provided with a downwardly depending flange 14 having at its upper end a shoulder 15 against which

the upper end of the tubular piston 11 abuts. The flange 14 closely embraces the upper portion of the tubular member 11; and preferably the parts are welded together around the edge 16 as indicated.

The external cylindrical surface of the cap

member 13 is accurately formed, as for example, by a grinding operation and constitutes a bearing and sealing surface for the vertically movable cylinder member 17. This cylinder member projects down around 70 and encircles the piston member 11 when the same is in lowered position. Furthermore the inner surface of the movable cylinder 17 is preferably polished, or accurately finished so that it works smoothly and in sealing 75 fashion against the exterior of the cap member 13. The vertical dimension of the bearing surface established between the cap member 13 (and the sealing gasket if used) and the inner surface of the cylinder member 17 80 is made sufficient to give the proper rigidity between the cylinder and piston members.

A plate 18 is placed over the upper end of the cylinder member and sealed thereto in fluid tight fashion as well as being connected with sufficient rigidity to carry the load of the platform and the automobile thereon. Preferably this plate 18 is of width greater than the diameter of the cylinder 17 as shown in Figure 1 and of length sufficient 90 to establish a satisfactory support for the cross or tabled plate as shown in Figure 3. A convenient system of attachment consists in placing a circular angle member 19 with its vertical flange around the upper portion 95 of the cylinder 17 and its horizontal flange in contact with the bottom surface of the plate 18. This vertical flange is then welded to the upper portion of the cylinder 17 and the horizontal flange may be bolted to the 100 plate 18, a fluid tight joint being provided by the use of a gasket or in any other suitable manner.

Surrounding the movable cylinder 17 is a ground shell 20. This ground shell is spaced from the movable cylinder 17 a sufficient distance to accommodate the travels of a stop ring 21 which is secured to the exterior surface of the movable cylinder 17 as by welding or otherwise. The ground shell 20 is of 110 sufficient size to permit the stop ring 21 to travel up and down within the movable cylinder and preferably without contact between the parts.

The lower end of the ground shell is sealed 115 and rigidly connected to the lower portion of the stationary piston member 11. In the particular construction illustrated this result is accomplished by the use of a ring 22 having its inner edge welded to the stationary piston 11 as shown at 23, and its outer edge welded to the lower end of the ground shell 120 as shown at 24.

This ring 22 or other closure for the ground shell is placed at such a position as 125 to serve as a support or rest for the lower end of the movable cylinder 17 when in the fully lowered position of Figure 1. In this way the weight of the movable cylinder together with the platform and the load there- 130

on may be directly supported and sustained in case the platform itself should not come into direct contact with the surface of the ground. I will state at this point, however, 5 that it is intended that normally the parts should be so set and proportioned that the end portions of the platform rails shall directly rest upon and be supported by the ground when lowered.

10 Usually the lower end of the ground shell 20 terminates above the lower end 12 of the stationary piston member 11. Such being the case the lowered portion of the piston member may be directly imbedded in concrete 15 or the ground as shown in Figures 1 and 2. This will make it possible to provide a very rigid and unyielding support for the lower portion of the stationary piston member and irrespective of the additional support accorded by the connection of the ground shell 20 to the piston member.

A stationary ground plate 25 is placed around the vertically movable cylinder at the ground level. This plate 25 has a central 25 opening 26 of slightly larger size than the movable cylinder 17 so that there is a slight clearance established as clearly indicated in Figure 1. The result is that normally the cylinder will rise and fall without actual 30 contact with the ground plate and therefore without any friction at this point. This fact makes it unnecessary to finish the exterior surface of the cylinder tube and the interior bore 26 of the ground plate, with corresponding 35 substantial saving in cost of manufacture. The amount of the clearance is, however, slight so that in case of lateral deflection being produced when the cylinder is raised and under load, the cylinder will come 40 into actual contact with the ground plate and be laterally supported against further deflection.

It will also be noticed that due to the slight 45 clearance existing between the cylinder and ground plate, the interior of the ground shell 20 is at atmospheric pressure and this is true even when the fluid pressure is exerted between the stationary piston and the movable cylinder during the raising and sustaining 50 the load.

Preferably the ground plate 25 is constructed with a flange 27 which reaches down into the upper end of the ground shell 20 and is welded thereto as shown at 28 in Figure 1. This flange is accommodated inside 55 of the upper portion of the ground shell and without necessary increase in the size of the ground shell which is made of sufficient size to receive the travels of the stop ring 21 already referred to.

When the cylinder is fully raised, the stop ring 21 comes into contact with the flange 27 so as to arrest any further upward movement of the cylinder.

60 For this purpose the ring 21 should be so

placed that the arresting contact takes place before the cylinder commences to override the flange 14 of the cap member 13 in upward travel. This will give assurance that the full amount of bearing contact is maintained between the cylinder 17 and the cap 13 at all times under load. 70

The cylinder 17 is sealed in fluid tight manner with respect to the cap 13. There is established the cylinder chamber 29 above 75 the cap and below the plate 18 and within the upper portion of the cylinder. A vertical pipe 30 extends up through the cap and into the space 29 and is preferably sealed to the cap where it passes through the same as 80 shown at 31.

The pipe 30 serves as a conduit to deliver fluid into the space 29 in order to raise the platform or to permit discharge of said fluid when the platform is to be lowered. The 85 arrangement illustrated may be conveniently used either for a liquid or oil operation or an air operation so-called. An oil operation arrangement is illustrated, for which purpose the pipe 30 is carried down to a 90 point close to the lower end 12 of the stationary piston 11. An air pipe 32 is passed through the lower portion of the stationary piston at a point below the ground shell 20 and into the interior of the stationary piston 11, and said pipe is then carried up to a point close to the top of the cap 13 as illustrated in Figure 1. Preferably the stationary piston 17 is then filled with oil up to a 95 level close to the upper end of the pipe 32. 100 (the movable cylinder being in the lowered position of Figure 1). Under these circumstances, introduction of compressed air through the pipe 32 will press down on the oil within the stationary piston, causing said oil to rise through the pipe 30 and into the space 29 above the cap 13. In such space 105 it will exert a lifting action on the plate 29 so as to raise the movable cylinder and the platform by oil operation. Conversely when the air is allowed to discharge from the pipe 32 the plate 18 and movable cylinder will descend, causing the oil to be restored through the pipe 30 into the stationary piston. 110

115 It will be noted from the above operation that the volume contained within the stationary tubular piston should be sufficient to accommodate the full amount of oil to be transferred during such lifting and lowering operations. The diameter of the stationary piston is somewhat less than the diameter of the movable cylinder 17; but conversely the length of the stationary hollow piston is preferably greater than the amount of displacing movement of the cylinder, especially in those cases in which it is desired to carry the lower end of the stationary piston down below the lower end of the movable cylinder so as to 120 get a direct ground support for the stationary 125 cylinder. 130

piston as shown in Figure 1. It is thus possible to establish the necessary tankage capacity for the oil directly inside of the device itself and without additional cost of construction or additional amount of structural materials and also to secure these results in a self-contained structure which can be fully assembled at the shop and set into place in a single installation operation.

10 It will be noted that the full fluid pressure is exerted within the space 29, tending to force a seepage of oil downwardly between the movable cylinder and the stationary head 13. This oil, however, will tend to serve as a

15 seal.

If desired, the sealing action between the movable cylinder and the stationary head 13 may be improved by the provision of an adjustable gland 33, which is forced down 20 against a packing ring 34. For this purpose the gland 33 is preferably provided with a cross piece and the pressure pipe 30 is carried up therethrough and receives a nut 35 which when tightened up serves to force the 25 gland down so as to compress the packing. When this arrangement is used it is preferred that the gland be vented to its bottom sides as shown at 36 so that the fluid pressure will be substantially balanced on the gland.

30 The plate 18 is provided with a removable cover 37 which when removed gives sufficient access to the nut 35 to enable the same to be adjusted in order to tighten the packing. The cap 37 when in place should be fluid tight 35 since it must resist the full fluid pressure when the lift is in service.

It will be noted that the pressure pipe 30 extends a slight distance above the cross piece of the gland 33. In case it should be desired 40 to operate this lift by air pressure direct, such operation may be accomplished by connecting the air pipe 32 directly to the pressure pipe 30 so that the compressed air is delivered directly into the space 29. Under such circumstances the lifting force will be directly established by compressed air exerted against the bottom face of the plate 18. In case of such operation it is nevertheless desirable to place a small amount of oil within the space 45 29 and on top of the cap therein, said oil establishing a seal around the packing gland and thus effectively lubricating the parts as well as eliminating any possible leakage at that point.

50 In connection with the foregoing it will be noted that the pipe 30 is carried up a slight distance into the space 29, so as to establish a weir which will retain a small amount of oil therein for the above sealing purpose.

55 In some cases it may be desirable to use an alternative sealing device such as a cup leather in place of the adjustable gland illustrated in Figure 1. For this purpose in Figure 9 I have illustrated a modified construction in 60 which the outside bearing surface of the cap

13' on the upper end of the stationary piston 11 is carried up to the top surface of the cap so as to establish the full bearing surface for the vertically movable cylinder 17. The fluid pressure pipe 30 is carried up through 70 the upper end of the cap and is welded or otherwise sealed thereto as shown at 31. Also the plate 18 is secured to the upper end of the vertically movable cylinder as in the previous construction, said plate also being provided 75 with the removable cap 37.

The packing gland 33 and packing material 34 are eliminated. In place thereof a cup leather 38 is located on the top of the cap 13, said cup leather having the upwardly 80 reaching flange 39 which bears and seals against the internal surface of the vertically movable cylinder 17.

A washer 40 is set down against the top 85 central surface of the cup leather 38 and is locked in place by a nut 41 threaded on to the upper projecting end of the pipe 30.

It will be noted that this cup leather can be reached for adjustment or renewal 90 through the plate 18 merely by removing the cap 37 when the platform is in lowered position.

The control of air or oil through the pipe 32 is effected in any convenient manner. In the arrangement illustrated, there is a pressure supply pipe 42 which supplies compressed air or other fluid under pressure from a supply tank or pump to a manifold 43. A raising valve 44 controls this supply. The pipe 32 connects to the manifold 43 by 100 means of a T 45. A vent valve 46 is also connected to the manifold 43.

In order to raise the lift, the valve 46 is kept closed and the valve 44 is opened. In 105 order to lower the lift the valve 44 is kept closed and the valve 46 is opened.

In those cases in which the lift is to be operated by oil or liquid, it becomes necessary to fill the hollow piston 11 with the same. For this purpose the vent valve 46 may be 110 opened (the pressure supply valve 44 being kept closed). The lift being in lowered position and relieved of pressure, the cap 37 may be removed. Upon pouring oil or other liquid down into the space 29 it will flow down through the pipe 30 and accumulate in the hollow piston 11, raising the level therein until finally the piston is completely filled up to the upper end of the pipe 32. Liquid 115 will then flow through the pipe 32 and finally come to a balance condition therein, the chamber 29 being completely filled. Thereupon the cap 37 may be secured in place and the lift is ready for normal operation.

120 Referring particularly to Figures 2 and 3, I have therein illustrated a suitable form of platform and track construction for automobile lifting service. In the arrangement illustrated, a cross plate 47 is secured to the 125 plate 18 by bolts or the like 48 so that the 130

platform as a whole may be removable. The plate 47 is carried out sidewise beyond the position of the plate 18. If desirable the side portions 49 and 50 of this plate 47 may be bent down so that its ends 51 and 52 are brought into direct contact with the surface of the ground as shown in Figure 1, although in some cases it may be desirable to carry the plate straight out at both sides.

10 Channel rails 53 and 54 have their central portions secured to the end portions 51 and 52 of the plate 47, the flanges of said channels reaching upwardly so as to establish tracks within which the automobile wheels will be guided. Preferably end flanges 55 and 56 are provided on the extreme ends of the plate 49 as abutments for the channel tracks.

15 If desired the channel tracks may be reinforced by vertical side plates 57 and 58 placed against the outside flanges of the channels and still further reenforcement may be produced by similar plates placed against the inside track channel flanges. These plates are secured by riveting, welding, or other 20 satisfactory means.

25 It will be noted that in those cases in which the plate 47 is carried straight out to both sides, the track channels 53 and 54 are supported some distance above the surface of the ground (it being assumed that the plate 18 on the upper end of the movable cylinder is supported above the plate 25 and that the latter is at ground level).

30 In order to bring the ends of the channel rails 53 and 54 down to ground level, I prefer to bend said ends downwardly at an easy slant as shown at 59 in Fig. 2, the extreme end 60 being cut off on a horizontal plane so that it will rest squarely on the ground and 35 be supported thereby. The amount of this downward deflection should in each case be made proper and sufficient to insure ground support for the ends of the rails when the lift is fully lowered, and this should be the case whether the plate 47 is bent down as 40 shown at 49 and 50 in Figure 1, or carried straight out to both sides.

45 In some cases it may be desirable to avoid the use of chocks for preventing the automobile wheels from running off of the rails except intentionally. For such purpose the end portions of the channels 53 and 54 may be bent upwardly a slight distance as shown at 50 in Figure 2 and in advance of the downwardly slanting portion 59. This will establish a hump of sufficient amount to prevent the wheel from rolling off, but not sufficient to prevent the car from being driven on or off of the lift.

55 It will be noted that the stationary hollow piston together with the cap 13, the vertically movable cylinder 17, the ground shell, the ground plate 25, the top or limit ring 21, and the internal pipes 30 and 32, together with other parts connected thereto may be as-

sembled as a complete unit in the shop and delivered fully assembled to the location of installation. The installation may then be easily made by merely setting the assembled unit down into the excavation and connecting up the pipe 32, for which purpose said pipe may be provided with a union coupling such as 62 as illustrated in Figure 1. The unit may be then permanently located by tamping in the surrounding earth, or in other specified manner.

60 It will be noted that in case of any slight seepage of oil past the cap 13, the same will collect in the lower portion of the ground shell and around the lower end of the vertically movable cylinder 17. Any such oil will thus serve a beneficial purpose in the sense that the lower end of the cylinder will dip into it each time the cylinder is fully lowered and such oil will be carried up and serves to lubricate against the cap 13 or against the ground plate 25 in case of deflection of sufficient amount to cause contact therewith.

65 In some cases it may even be desirable to introduce oil into the ground shell in amount sufficient to cause substantial submergence of the cylinder 17 when lowered so as to insure lubrication of the outside of the same each time the lift is lowered and thus always insure lubrication of the outside of the cylinder 70 on the succeeding raising operation and in case of contact between the exterior surface of the cylinder and the ground plate 25.

75 While I have herein shown and described only certain embodiments of the features of my present invention, still I do not intend to limit myself thereto except as I may do so in the claims.

I claim:

1. A lift for the purpose specified, including in combination a stationary vertical tubular piston member having its lower end sealed in liquid tight fashion, a cap closing the upper end of said piston member in liquid tight fashion and having a cylindrical external bearing surface of substantial vertical dimension, a vertically movable tubular cylinder member slidably mounted on and sealing against the bearing surface aforesaid and having bearing contact therewith for a substantial vertical distance, a stationary cylindrical ground shell surrounding the cylinder member and having its lower end secured to the piston member at the lower limit of movement of the lower end of the cylinder member and a substantial distance above the lower end of the piston member, and serving as a bottom rest for the cylinder member when in lowered position, the ground shell and the piston member below the line of junction of the ground shell therewith being imbedded in concrete, a circular ground plate secured to the upper end of the ground shell and having an inwardly reaching circular bearing surface having clearance from the external 100

surface of the cylinder member and serving to limit lateral deflection thereof under load and when elevated, an outwardly reaching stop ring on the exterior of the cylinder member in position to engage the inwardly reaching circular bearing surface aforesaid to arrest upward movement of the cylinder member before the same overrides the cylindrical exterior bearing surface of the cap aforesaid, a sealing member on the upper end of the cap having sealing contact with the inner surface of the cylinder member during vertical movement thereof, a platform mounted on and secured to the upper end of the cylinder member in liquid tight fashion, a cover thereon removable to give access to the sealing member aforesaid, and air pipe extending through the lower portion of the piston member and reaching upwardly thereinto to a position close to the cap aforesaid, a liquid pipe within the piston member reaching from a position close to the bottom thereof and up through the cap in liquid tight fashion into the space within the cylinder member to transfer liquid between the interior portions of the piston member and the cylinder member under air control, air pressure delivery and discharge lines in connection with the air pipe aforesaid, valves in said lines, and suitable liquid within the piston and cylinder members, substantially as described.

2. A lift for the purpose specified, including in combination a stationary vertical tubular piston member having its lower end sealed in liquid tight fashion, a cap closing the upper end of said piston member in liquid tight fashion and having a cylindrical external bearing surface of substantial vertical dimension, a vertically movable tubular cylinder member slidably mounted on and sealing against the bearing surface aforesaid and having bearing contact therewith for a substantial vertical distance, a stationary cylindrical ground shell surrounding the cylinder member and having its lower end secured to the piston member at the lower limit of movement of the lower end of the cylinder member and a substantial distance above the lower end of the piston member, and serving as a bottom rest for the cylinder member when in lowered position, the ground shell and the piston member below the line of junction of the ground shell therewith being imbedded in concrete, a circular ground plate secured to the upper end of the ground shell and having an inwardly reaching circular bearing surface having clearance from the external surface of the cylinder member and serving to limit lateral deflection thereof under load and when elevated, an outwardly reaching stop ring on the exterior of the cylinder member in position to engage the inwardly reaching circular bearing member aforesaid to arrest upward movement of the cylinder member before the same overrides the cylindrical exterior bearing surface of the cap aforesaid, a sealing member on the upper end of the cap having sealing contact with the inner sur-

face of the cylinder member during vertical movement thereof, a platform mounted on and secured to the upper end of the cylinder member in liquid tight fashion, a cover thereon removable to give access to the sealing member aforesaid, an air pipe extending through the lower portion of the piston member and reaching upwardly therein to a position close to the cap aforesaid, a liquid pipe 10 within the piston member reaching from a position close to the bottom thereof and up through the cap in liquid tight fashion into the space within the cylinder member to transfer liquid between the interior portions 15 of the piston member and the cylinder member under air control, and suitable liquid within the piston and cylinder members, the space within the piston member being at least equal to the volume of the cylinder member 20 displaced during the maximum vertical movement of the cylinder member, substantially as described.

4. A lift for the purpose specified, including in combination a stationary vertical tubular piston member having its lower end sealed in liquid tight fashion, a cap closing the upper end of said piston member in liquid tight fashion and having a cylindrical external bearing surface of substantial vertical dimension, a vertically movable tubular cylinder member slidably mounted on and sealing against the bearing surface aforesaid and having bearing contact therewith for a substantial vertical distance, a stationary cylindrical ground shell surrounding the cylinder member and having its lower end secured to the piston member at the lower limit of movement of the lower end of the cylinder member and a substantial distance above the lower end of the piston member, and serving as a bottom rest for the cylinder member when in lowered position, a circular ground plate secured to the upper end of the ground shell and having an inwardly reaching circular bearing surface serving to limit lateral deflection thereof under load and when elevated, an outwardly reaching stop ring on the exterior of the cylinder member in position to engage the inwardly reaching circular bearing member aforesaid to arrest upward movement of the cylinder member before the same overrides the cylindrical exterior bearing surface of the cap aforesaid, a sealing member on the upper end of the cap having sealing contact with the inner surface of the cylinder member during vertical movement thereof, a platform mounted on and secured to the upper end of the cylinder member in liquid tight fashion, a cover thereon removable to give access to the sealing member aforesaid, and means for introducing and

permitting discharge of fluid pressure under control into the space within the cylinder member, substantially as described.

5. A lift for the purpose specified, including in combination a stationary vertical tubular piston member having its lower end sealed in liquid tight fashion, a cap closing the upper end of said piston member in liquid tight fashion and having a cylindrical external bearing surface of substantial vertical dimension, a vertically movable tubular cylinder member slidably mounted on and sealing against the bearing surface aforesaid and having bearing contact therewith for a substantial vertical distance, a stationary cylindrical ground shell surrounding the cylinder member and having its lower end secured to the piston member at the lower limit of movement of the lower end of the cylinder member and a substantial distance above the lower end of the piston member, and serving as a bottom rest for the cylinder member when in lowered position, a circular ground plate secured to the upper end of the ground shell and having an inwardly reaching circular bearing surface serving to limit lateral deflection thereof under load and when elevated, an outwardly reaching stop ring on the exterior of the cylinder member in position to engage the inwardly reaching circular bearing member aforesaid to arrest upward movement of the cylinder member before the same overrides the cylindrical exterior bearing surface of the cap aforesaid, a sealing member on the upper end of the cap having sealing contact with the inner surface of the cylinder member during vertical movement thereof, a platform mounted on and secured to the upper end of the cylinder member in liquid tight fashion, a cover thereon removable to give access to the sealing member aforesaid, and means for introducing and permitting discharge of fluid pressure under control into the space within the cylinder member, substantially as described.

6. A lift for the purpose specified, including in combination a stationary vertical tubular piston member having its lower end sealed in liquid tight fashion, a cap closing the upper end of said piston member in liquid tight fashion and having a cylindrical external bearing surface of substantial vertical dimension, a vertically movable tubular cylinder member slidably mounted on and sealing against the bearing surface aforesaid and having bearing contact therewith for a substantial vertical distance, a stationary cylindrical ground shell surrounding the cylinder member and having its lower end secured to the piston member at the lower limit of movement of the lower end of the cylinder member and a substantial distance above the lower end of the piston member, and serving as a bottom rest for the cylinder member when in lowered position, a circular ground plate

secured to the upper end of the ground shell and having an inwardly reaching circular bearing surface serving to limit lateral deflection thereof under load and when elevated, an outwardly reaching stop ring on the exterior of the cylinder member in position to engage the inwardly reaching circular bearing member aforesaid to arrest upward movement of the cylinder member before the same overrides the cylindrical exterior bearing surface of the cap aforesaid, a platform mounted on and secured to the upper end of the cylinder member in liquid tight fashion, and means for introducing and permitting discharge of fluid pressure under control into the space within the cylinder member, substantially as described.

7. A lift for the purpose specified, including in combination a stationary vertical tubular piston member having its lower end sealed in liquid tight fashion, a cap closing the upper end of said piston member in liquid tight fashion and having a cylindrical external bearing surface of substantial vertical dimension, a vertically movable tubular cylinder member slidably mounted on and sealing against the bearing surface aforesaid and having bearing contact therewith for a substantial vertical distance, a stationary cylindrical ground shell surrounding the cylinder member and having its lower end secured to the piston member at the lower limit of movement of the lower end of the cylinder member a circular ground plate secured to the upper end of the ground shell and having an inwardly reaching circular bearing surface serving to limit lateral deflection thereof under load and when elevated, an outwardly reaching stop ring on the exterior of the cylinder member in position to engage the inwardly reaching circular bearing member aforesaid to arrest upward movement of the cylinder member before the same overrides the cylindrical exterior bearing surface of the cap aforesaid, a platform mounted on and secured to the upper end of the cylinder member in liquid tight fashion, and means for introducing and permitting discharge of fluid pressure under control into the space within the cylinder member, substantially as described.

8. A lift for the purpose specified, including in combination a stationary vertical tubular piston member having its lower end sealed in liquid tight fashion, a cap closing the upper end of said piston member in liquid tight fashion and having a cylindrical external bearing surface of substantial vertical dimension, a vertically movable tubular cylinder member slidably mounted on and sealing against the bearing surface aforesaid and having bearing contact therewith for a substantial vertical distance, a stationary cylindrical ground shell surrounding the cylinder member and having its lower end secured to the piston member at the lower limit of movement of the lower end of the cylinder

member, means for limiting the upward movement of the cylinder member before the same overrides the cylindrical exterior bearing surface of the cap aforesaid, a platform mounted on and secured to the upper end of the cylinder member in liquid tight fashion, and means for introducing and permitting discharge of fluid pressure under control into the space within the cylinder member, substantially as described.

9. A lift for the purpose specified, including in combination a stationary vertical tubular piston member having its lower end sealed in liquid tight fashion, a cap closing the upper end of said piston member in liquid tight fashion and having a cylindrical external bearing surface of substantial vertical dimension, a vertically movable tubular cylinder member slidably mounted on and sealing against the bearing surface aforesaid and having bearing contact therewith for a substantial vertical distance, a stationary cylindrical ground shell surrounding the cylinder member, a circular ground plate secured to the upper end of the ground shell and having an inwardly reaching circular bearing surface serving to limit lateral deflection of the cylinder member under load and when elevated, an outwardly reaching stop ring on the exterior of the cylinder member in position to engage the inwardly reaching circular bearing member aforesaid to arrest upward movement of the cylinder member before the same overrides the cylindrical exterior bearing surface of the cap aforesaid, a platform mounted on and secured to the upper end of the cylinder member in liquid tight fashion, and means for introducing and permitting discharge of fluid pressure under control into the space within the cylinder member, substantially as described.

10. A lift for the purpose specified including in combination a stationary vertical tubular piston member, a cap closing the upper end of said piston member in liquid tight fashion and having a cylindrical external bearing surface of substantial vertical dimension, a vertically movable tubular cylinder member slidably mounted on and sealing against the bearing surface aforesaid and having bearing contact therewith for a substantial vertical distance, a stationary cylindrical ground shell surrounding the cylinder member, a circular ground plate secured to the upper end of the ground shell and having an inwardly reaching circular bearing surface serving to limit lateral deflection of the cylinder member under load and when elevated, an outwardly reaching stop ring on the exterior of the cylinder member in position to engage the inwardly reaching circular bearing member aforesaid to arrest upward movement of the cylinder member before the same overrides the cylindrical exterior bearing surface of the cap aforesaid, a platform mounted on and secured to the upper end of the cylinder member in liquid tight fashion, and means for introducing and permitting discharge of fluid pressure under control into the space within the cylinder member, substantially as described.

- drical exterior bearing surface of the cap aforesaid, a sealing member on the upper portion of the cap serving to establish sealing contact with the interior surface of the cylinder member, a platform mounted on and secured to the upper end of the cylinder member in liquid tight fashion and having a portion which is removable to give access to said sealing member for adjustment and renewal purposes, and means for introducing and permitting discharge of fluid pressure under control into the space within the cylinder member, substantially as described.
11. A lift for the purpose specified including in combination a stationary vertical tubular piston member, a cap closing the upper end of said piston member in liquid tight fashion and having a cylindrical external bearing surface of substantial vertical dimension, a vertically movable tubular cylinder member slidably mounted on and sealing against the bearing surface aforesaid and having bearing contact therewith for a substantial vertical distance, a stationary cylindrical ground shell surrounding the cylinder member, a sealing member on the upper portion of the cap serving to establish sealing contact with the interior surface of the cylinder member, a platform mounted on and secured to the upper end of the cylinder member in liquid tight fashion and having a portion which is removable to give access to said sealing member for adjustment and renewal purposes, and means for introducing and permitting discharge of fluid pressure under control into the space within the cylinder member, substantially as described.
12. A lift for the purpose specified including in combination a stationary vertical piston member, a head mounted upon the upper end thereof and supported thereby and having a cylindrical external bearing surface of substantial vertical dimension, a vertically movable tubular cylinder member slidably mounted on and sealing against the bearing surface aforesaid and having bearing contact therewith for a substantial vertical distance, a stationary cylindrical ground shell surrounding the cylinder member, a circular ground plate secured to the upper end of the ground shell and having an inwardly reaching circular bearing surface serving to limit lateral deflection of the cylinder member under load and when elevated, an outwardly reaching stop ring on the exterior of the cylinder member in position to engage the inwardly reaching circular bearing member aforesaid to arrest upward movement of the cylinder member before the same overrides the cylindrical exterior bearing surface of the head aforesaid, a sealing member on the upper portion of the head serving to establish sealing contact with the interior surface of the cylinder member, a platform mounted on and secured to the upper end

of the cylinder member in liquid tight fashion and having a portion which is removable to give access to said sealing member for adjustment and renewal purposes, and means for introducing and permitting discharge of fluid pressure under control into the space within the cylinder member, substantially as described.

13. A lift for the purpose specified including in combination a stationary vertical piston member having a head block on its upper end, said head block having a cylindrical external bearing surface of substantial vertical dimension, a vertically movable tubular cylinder member slidably mounted on and sealing against the bearing surface aforesaid and having bearing contact therewith for a substantial vertical distance, a sealing member on the upper portion of the head block serving to establish sealing contact with the interior surface of the cylinder member, a platform mounted on and secured to the upper end of the cylinder member in liquid tight fashion and having a portion which is removable to give access to said sealing member for adjustment and renewal purposes, and means for introducing and permitting discharge of fluid pressure under control into the space within the cylinder member, substantially as described.

14. A lift for the purpose specified including in combination a stationary vertical piston member having a rigid support for its lower end, a vertically movable tubular cylinder member surrounding said piston member and having sealing and sliding contact therewith throughout the normal range of movement of said cylinder member, a ground plate surrounding the cylinder member and having a bearing surface adapted to limit lateral deflection of the cylinder member under load and when elevated, an external outwardly projecting ring portion on the cylinder member in position to engage said ground plate and limit upward movement of the cylinder member before it disengages from the piston member, a sealing member on the upper portion of the piston member making sealing contact with the interior surface of the cylinder member, a platform mounted on and secured to the upper end of the cylinder member in liquid tight fashion and having a portion which is removable to give access to said sealing member for adjustment and renewal purposes, and means for introducing and permitting discharge of fluid pressure under control into the space within the cylinder member, substantially as described.

15. A lift for the purpose specified including in combination a stationary vertical piston member having a rigid support for its lower end, a vertically movable tubular cylinder member surrounding said piston member and having sealing and sliding contact

therewith throughout the normal range of movement of said cylinder member, a ground plate surrounding the cylinder member and having a bearing surface adapted to limit 5 lateral deflection of the cylinder member under load and when elevated, means for limiting upward movement of the cylinder member before it disengages from the piston member, a sealing member on the upper portion 10 of the piston member making sealing contact with the interior surface of the cylinder member, a platform mounted on and secured to the upper end of the cylinder member in liquid tight fashion and having 15 a portion which is removable to give access to said sealing member for adjustment and renewal purposes, and means for introducing and permitting discharge of fluid pressure under control into the space within the cylinder member, substantially as described. 20

16. A lift for the purpose specified including in combination a stationary vertical piston member having a rigid support for its lower end, a vertically movable tubular member 25 surrounding said piston member and having sealing and sliding contact therewith throughout the normal range of movement of said cylinder member, means adjacent to the exterior of the cylinder member substantially 30 at the location of the ground level adapted to limit lateral deflection of the cylinder member under load and when elevated, means for limiting the upward movement of the cylinder member before it disengages from 35 the piston member, a platform mounted on and secured to the upper end of the cylinder member in liquid tight fashion, and means for introducing and permitting discharge of fluid pressure under control into the space 40 within the cylinder member, substantially as described.

17. A lift for the purpose specified, including in combination a stationary vertical tubular piston member having its upper and 45 lower ends sealed in liquid tight fashion, a vertically movable tubular cylinder member surrounding said piston member and vertically movable with respect thereto in sealing contact therewith, a platform mounted on and secured to the upper end of the cylinder member in liquid tight fashion, an air pipe 50 extending through the lower portion of the piston member and reaching upwardly therein to a position close to the upper end thereof, a liquid pipe within the piston member reach-

ing from a position close to the bottom thereof and up through the upper end thereof into the space within the cylinder member to transfer liquid between the interior portions of the piston member and the cylinder member 70 under air control, and means for controlling the delivery and release of air through said air pipe, the space within the piston member being at least equal to the volume of the cylinder member displaced during maximum vertical movement of the cylinder member, substantially as described. 75

18. A lift for the purpose specified, including in combination a stationary vertical tubular piston member having its upper and lower ends sealed in liquid tight fashion, a vertically movable tubular cylinder member surrounding said piston member and vertically movable with respect thereto in sealing contact therewith, a platform mounted 80 on and secured to the upper end of the cylinder member in liquid tight fashion, the space within the piston member being at least equal to the volume of the cylinder member displaced during maximum vertical movement 85 of the cylinder member, suitable liquid within the piston member, and means for transferring said liquid from the tubular piston member under pressure and control into the space within the cylinder member to lift said member and for permitting redelivery of said liquid from the cylinder member back into the tubular piston member, substantially as described. 90

19. A lift for the purpose specified, including in combination a stationary vertical tubular piston member having its upper and lower ends sealed in liquid tight fashion, a vertically movable tubular cylinder member surrounding said piston member and vertically movable with respect thereto in sealing contact therewith, a platform mounted on and secured to the upper end of the cylinder member in liquid tight fashion, the space within the piston member being at least equal to the volume of the cylinder member displaced during maximum vertical movement of the cylinder member, suitable liquid within the tubular piston member, and means for transferring said liquid under control between the tubular piston member and the cylinder member to thereby control the raising and falling of the cylinder tube, substantially as described. 105
